UNITED STATES PATENT OFFICE.

JOHN S. LITTLEFORD, JR., OF FORT THOMAS, KENTUCKY.

INDOOR GAME.

Application filed November 9, 1926. Serial No. 147,351.

This invention relates to indoor games and more particularly to a game of miniature golf, or a game in imitation of the well-known outdoor game of "golf".

5 Some of the objects of this invention are to provide a game of this character, which will be highly entertaining, instructive, and one which encourages the exercise of skill and judgment on the part of the players.

10 Other objects will also appear in the specification taken in connection with the accompanying drawing wherein one form of the invention is illustrated.

The invention consists in providing an imitation golf course represented as by printing on heavy paper or cloth, such as 15 felt, together with hazards such as "bunkers," an imitation golf ball constructed so as to retard or kill the roll, and a catapult or 20 shooter for driving the balls from tee to green.

The invention also consists in the construction, combination, location and arrangement of parts as herein set forth and 25 claimed.

In the drawings:

Fig. 1 is a perspective view of the cloth course, clearly showing the hazards, bunkers, tees, greens, flags, etc.;

30 Fig. 2 is a plan view of the catapult or shooter;

Fig. 3 is a longitudinal vertical section of the catapult taken on a plane corresponding to line 3—3 of Fig. 2;

35 Fig. 4 is an enlarged view of one of the green flags, the base of which is shown in vertical section;

Fig. 5 is a side elevation of one of the bunkers;

40 Fig. 6 is a plan view thereof;

Fig. 7 is a central vertical section of one of the imitation golf balls showing it partly loaded with weighted material, such as "shot" which overcomes the roll of the 45 ball; and

Fig. 8 is a side elevation of the catapult illustrating the range or distance of various "shots."

In the embodiment of my invention as 50 illustrated and which shows a preferred construction, I provide a miniature golf course *a* represented upon heavy paper or cloth, such as green felt, upon which hazards are printed to represent sand traps *b*, woods *c* and pond *e*. Tees *f*, greens *g* and *h* and 55 island area *i* are also represented upon the

cloth course *a* by printing or otherwise, as clearly shown in Fig. 1.

Upon each of the greens *g* and *h*, I provide flags comprising standard *k*, flag *d* and 60 base *m*. The outer periphery of base *m* is beveled or tapered at *n* and is provided in the center with boss *o* through which a hole *p* is drilled to receive the lower end of standard *k*. The upper face of base *m* is 65 cut away to form recess or cup *q*, as clearly shown in the sectional view, Fig. 4. The lower end of standard *k* is provided with ears *r* for the purpose of supporting said standard within hole *p* of base *m*. Flag *d* 70 is preferably made of thin stiff material, such as tin, and is soldered to the upper end of standard *k*.

The imitation golf ball *s* is preferably made of celluloid or similar light material 75 and is provided on its inside with weighted material, such as shot *t*, for purposes more fully explained hereinafter.

The catapult or driver *u* comprises base *v*, the bottom of which is curved, as at *w* and spring member *x* which is securely fastened to said base *v* in any suitable manner, as for example, by wood screws *y*. Said spring-member *x* is provided with grooved recesses or depressions *w'* and *w''*, as clearly shown 85 in Figs. 2 and 3 and 8, respectively.

Directions for playing.—This invention is an eighteen hole game of table golf that requires the same degree of perseverance, judgment and skill that makes the real game of 90 golf so fascinating.

The equipment.—The equipment necessary to play this game consists of one "course" or table felt *a*, two flags and standards *d* and *k*, respectively, two flag bases *m*, four 95 bunkers *j*, four balls *s*, one "driver" or catapult *u* and two score pads.

The set-up.—Spread the felt course *a* smoothly on a table and place the flags *d*, properly mounted in their bases *m*, on the "greens" or small enclosed areas *g* and *h*, respectively, as shown in Fig. 1. Place the bunkers *j* on the rectangular areas as outlined. Set the driver or catapult *u* on the circle numbered "1" (number one "tee") 105 and the game is ready to play.

Number of players.—Any number of persons may play the game but the most pleasure is derived when playing a competitive "two-some" (two players) or "four-some" (four 110 players). Look under the heading "Golf terms".

Object of the game.—The object of the game is to shoot the ball *s* with the catapult or "driver" *u* and have it stop on one of the greens *g* or *h*. If this is done with the 5 first shot the player makes a score of two for that hole, or if on the first shot the ball *s* stops in the "cup" or recessed portion *g* of the flag base *m*, he makes a score of one. However, if the ball fails to reach the green 10 15 20 25 30 35 40 45 50 55 60 65 played for on the first shot, the player counts one, two or three, depending upon the location of the ball, and continues to shoot or drive from the "tee" position until the ball is made to stop on the green. In computing his score for the hole the player will take the total of all of his shots using the values for each shot as given below.

Ball in the "cup" *f* counts one.

Ball on the "green" *g* or *h* counts two.

Ball on the "fairway" *z* (all of the area outside of "sand traps", "greens", "pond", etc.) counts one.

Ball in a "sand trap" *b*, in the "pond" *e*, or in the "woods" *c* counts two or three according to its location. (See penalties marked on felt).

Ball out of bounds (on or over the border line *a'* of the course *a*) counts two.

Ball on top of a bunker *j* counts one. If a ball stops directly on the border of a "trap" *b*, "pond" *e* or "green" *g* or *h* it is considered to be in the "fairway" *z* and counts one.

Any ball that "slips" or rolls from the driver *u* when it is in the hands of the player will be counted as a shot and will be given a value of one, two or three in accordance with the count given above.

Examples of scoring.—Let it be supposed that a player shoots his first shot and it stops in the "fairway" *z* he then counts one and without moving the driver or catapult *u* from the tee position *f* he again places the ball *s* on the spring *x* and shoots a second time. If his second shot stops in the pond *e* he adds two to his score, making a total of three and shoots a third time. If the third shot stops on the green *g* or *h* he then adds two to his score and has made a total score of five for that hole. The next player then shoots.

The island.—It will be noticed that there is an area *i* marked off within the pond *e* that will be known as "the island". Ordinarily any ball that stops upon this island 55 will be considered in the "fairway" *z* and will count one, however should any player shoot a score or five or more without reaching the green, he may if he chooses, shoot for the island and if successful in reaching it, may deduct five from his score. He then shoots for the green until he reaches it or "holes out". The privilege of shooting for the island is extended to a player but once on each hole and all unsuccessful shots that 60 65 are made for the island are counted the same

as if the player had been shooting for the green.

Even though it is unintentional upon the part of the player, a shot that stops on the island deducts five from his score, provided his score at the time is five or more and that he has not used the privilege before on this same hole.

Playing around the course.—The layout of the course *a* provides for playing eighteen 75 holes. That is, each player plays around the table twice, shooting for the first nine holes to the flag *d* and "green" *g* located nearest to the number 1 "tee" and for the second round or, tenth to the eighteenth hole, to the 80 "green" *h* at the far end of the table. For the order in which players shoot see "The honor" under the heading of "Golf terms".

Using the driver or catapult.—To properly use the "driver" or catapult *u* it should 85 be held firmly between the thumb and fingers of the left hand, at the same time pressing it securely against the felt or course *a*. With the driver pointing directly at the flag, place the ball *s* in one of the depressions or 90 recesses *x'* or *x''* in the spring-member *x* and with the thumb or forefinger of the right hand depress said spring-member *x* and then let the thumb or finger slip off quickly. The forward depression *x''* in the 95 spring should be used on short, high or "mashie" shots and the rear depression *x'* for the longer shots. The flight or altitude of the ball may be controlled by "laying the driver back" or rolling it to the rear on its 100 curved base for high shots and by pitching it forward to gain distance, as illustrated in Fig. 8.

It will be noted that the spring *x* must be pressed straight down otherwise the ball 105 *s* will be "hooked" (thrown to the left) or "sliced" (thrown to the right).

Altering the play.—The positions of the flags *d* on the greens *g* and *h*, respectively, may be changed occasionally, thus altering 110 the length of each hole and changing the character of the shots required from the various "tees" *f*.

Golf terms.—"Two-some": A match composed of two players. 115

"Four-some": A match composed of four players. In this case two of the players play as partners and are opposed to the other two.

"Low-ball": The score of the player who 120 makes a hole in the least number of strokes.

"The honor": The privilege of shooting first from the "tee." The person having the "low ball" on the last hole played is granted this privilege.

"Winning the hole": A player wins the hole when his score for the hole is better than that of his opponent.

"Match play": Playing around the course and counting each "low ball" as one winning 130

point. The player having the greatest number of "low balls" wins the match.

"Medal play": Playing around the course with the object of completing the round in the least possible strokes. The player with the lowest total for all of the holes played wins the match in "medal play."

It will be understood that certain changes and modifications of my invention can be made without departing from its scope or spirit as defined in the claims.

What I claim as new and desire to secure by Letters Patent is:

1. In a game of the character described, including a miniature golf course, a ball, a driver having a curved or rocker-shaped bottom with a curved spring mounted thereon and having a depression to engage the ball, substantially as set forth and for the purposes specified.

2. In a game of the character described, including a miniature golf course, a ball, a driver having a curved or rocker-shaped bottom with a spring mounted thereon and having a depression to engage the ball, substantially as set forth and for the purposes specified.

3. In a game of the character described, including a miniature golf course, a driver, a hollow ball adapted to be mounted on and thrown by said driver over said golf course and having a plurality of shot therein, substantially as set forth and for the purposes specified.

35 4. In a game of the character described, including a miniature golf course, a rocker-shaped driver adapted to be mounted on said golf course and having a spring thereon and a ball adapted to be mounted thereon and thrown therefrom at varying angles, depending upon the position of the rocker-shaped member of said driver while the spring is being actuated.

45 5. In a game of the character described, the combination of a miniature golf course

represented upon a flexible material, a driver having a spring member mounted thereon, an imitation golf ball adapted to be played across said course as by being projected from said driver, and hazards represented upon said course in the form of bunkers, sand traps, ponds and woods, substantially as described.

6. In a game of the character described, a piece of felt having a miniature golf course represented thereon, a driver, a spring on said driver, an imitation golf ball, said ball being hollow and partially filled with weighted material so as to retard the "roll" of said ball, bunkers, said bunkers adapted to be placed upon said course as desired, imitation sand traps, woods, and ponds represented upon said course, greens represented upon said course and flags adapted to be placed upon said greens, substantially as described.

7. In a game of the character described, in combination, a course, comprising a piece of resilient material such as felt, hazards thereon in the form of sand traps, ponds and woods, obstructions placed upon said course in the form of bunkers, greens on said course, flags adapted to be placed upon said greens, an imitation golf ball, a driver having means mounted thereon to throw or project said ball, substantially as described.

8. In combination with a miniature golf course represented upon pliable material such as felt and having greens, ponds, woods, sand traps, etc. represented thereon, a driver comprising a body portion having a curved bottom, a spring-member having a plurality of depressions therein and mounted upon said body portion, and a miniature golf ball adapted to be placed on said depressions and thrown therefrom, substantially as set forth and for the purposes specified.

JOHN S. LITTLEFORD, JR.
